(57) **CLAIM**

The ornamental design for the beverage packet holder, as shown and described.

DESCRIPTION

FIG. 1 is an isometric view of the coffee pack holder of this invention;

FIG. 2 is a top view thereof;

FIG. 3 is a bottom view;

FIG. 4 is a front view;

FIG. 5 is a back view;

FIG. 6 is a left side view; and,

FIG. 7 is a right side view of the invention.

1 Claim, 2 Drawing Sheets

FIG. 1

FIG. 2

FIG. 4

FIG. 5

FIG. 3

FIG. 6

FIG. 7
